UNITED STATES PATENT OFFICE.

CHARLES B. BOYLE, OF NEW YORK, N. Y., ASSIGNOR TO THE BOYLE ILLUMINATING COMPANY, OF SAME PLACE.

LAMP.

SPECIFICATION forming part of Letters Patent No. 295,479, dated March 18, 1884.

Application filed August 25, 1882. Renewed August 23, 1883. (No model.)

To all whom it may concern:

Be it known that I, CHARLES B. BOYLE, a citizen of the United States, residing in the city of New York, in the county of New York 5 and State of New York, have invented a new and useful Improvement in Lamps for Burning Mineral and other Oils, (for which I have not yet applied for a patent in any foreign country,) of which the following is a specification.

My invention relates to improvements in vase-lamps in which the tank or reservoir holding the oil has a perpendicular central draft-tube surrounded by a draft-chamber, both communicating with the air through the bottom of the oil-tank, from whence all the air which supplies the flame with oxygen is drawn. The porcelain or other vase, in the top of which the oil-tank is placed, is pierced in its bottom 20 or near its base with a sufficient number of small openings to admit all the air required for the supply of the flame, and sufficient in excess to keep a constant air-current flowing upward between the oil-tank and the vase and 25 passing out through orifices in the top of the latter. I attain these results by the construction shown in the accompanying drawings.

Figure 1 of the drawings herewith submitted is a full-sized vertical central section of a round-wick lamp now in use. Fig. 2 is a vertical section of my removable burner detached.

A is the oil-tank; B B, the annular air-chamber; C C, an annular oil-chamber, down into which the wick extends from the burner, and 35 D is the central air-chamber.

The bent arrows F F indicate the flow of the oil through the horizontal tubes E E from the tank A A into the wick-chamber C C.

The bottom of the wick-chamber is closed, 40 like that of the tank.

The walls and bottom of the vase are indicated by the letter V.

The openings g g show two of a system of perforations which pass through the bottom 45 of the vase for the purpose of admitting air, and the system of arrowed and dotted lines shows the entrance of the air and its distribution after entering the vase, one portion passing up to the flame through the central tube, 50 D, and the annular chamber B B, and another portion, H H, passing upward between the in-

terior wall of the vase and the exterior wall of the tank, and making its exit through notches or perforations J in the top of the vase, as shown by the arrows.

The height of the tubes which inclose the wick-chamber C C is indicated by the arrows K K, the inner tube being a little the higher, in order to facilitate the entrance of the wick and wick-tube of the burner while it is being 60 screwed to its place.

The tube which forms the exterior wall of the air-chamber B B has its upper termination against the top of the oil-tank, to which it is soldered at L L.

The tubes which form the walls of the annular air-chamber B B are held in their place at the bottom by the cross-tubes E E and at the top by thin checks M M. The continuation of the air-chamber B B through the burner has its 70 walls held together and concentric by similar checks, while the interior tube of the burner is held concentrically by a substantial connection of reasonably thick sheet metal, N, which is firmly set into the walls of the wick-chamber and soldered to them. The edges of the wick pass down on either side of this connection.

The projections O O show the cross-sections of a ring on the outside of the burner, forming a rest for the chimney, which comes down far enough to require no outside holder.

The burner screws onto the lamp, as shown at S.

The wick is raised and lowered by the ordinary mechanical means now so commonly in use.

P is an opening for filling the lamp, R a cup for receiving any oil which may drop from the center tubes, and T a bolt which fastens 90 the vase to its pedestal.

I am aware that central draft-tubes through the body of lamps, similar to that represented at D, have been used in connection with surrounding annular wick and air passages, and 95 also that it is not new to cause a circulation of air between the oil-reservoir and its containing-vase; but I am not aware that these several devices have been combined in the manner I have herein described; nor am I aware 100 that a burner having tubes forming supplemental or extension draft-passages has been

before used in combination with a central-draft lamp.

What I claim, therefore, as new in the above-described invention is—

- 5 1. In combination with the vase V, having apertures *g* in its base, and exits J at top, the lamp-reservoir A, having a flange at top, to adapt it to hang on the edge of the vase and permit the circulation of air freely around the font and through the exits J, as and for the purpose set forth.
- 10 2. In combination with the vase V, having perforated base, and exits J at top, the oil-reservoir A, hung within said vase, so as to leave a free air-space, H, and central and an-

nular air-passages, D and B, the apertures *g* in the vase being of sufficient area to provide a free supply of air to the three air-passages D, B, and H, as set forth.

3. In combination with an oil-reservoir having central air-chamber and surrounding annular wick and air passages, the removable burner and wick carrier adapted to be screwed upon the reservoir, and having corresponding central air-tube and surrounding annular wick and air passages, as set forth. 20 25

CHARLES B. BOYLE.
